SEA ANCHOR

Leonard P. Frieder, Great Neck, and Walter S. Finken, Brooklyn, N. Y.; said Finken assignor to said Frieder

Application December 7, 1945, Serial No. 633,357

4 Claims. (Cl. 114—209)

1
This invention relates to a sea anchor that is particularly useful for retarding the rate of drift of vessels under wind pressure and for increasing the rate of drift in water currents. This sea anchor can be made of such sizes that it is useful for vessels of sizes from that of a small life raft to that of an ocean steamer. It also keeps the vessels into the wind and waves.

It is well known that when ships go down and people are transferred to rafts or small boats after the positions of the ships have been broadcast, such rafts are frequently driven by wind far from the scene before rescuers arrive.

By the present invention one or more sea anchors may be provided for each boat which prevent the rafts or boats from being blown by the wind so far away as to prevent the same from being found. The sea anchor not only holds the rafts or boats into the wind, but it also retards wind drift.

In addition to holding the bow of a vessel head up into the wind, this sea anchor maintains a relatively fixed position of the vessel to which it is attached because of its property of exerting a strong drag. This is advantageous because ocean currents are well charted both as to velocity and direction. Wind, however, varies considerably in many localities both as to velocity and direction.

When the present sea anchor is inflated it will move without yawing in a direction that is determined in accordance with the greater force that is applied to it by the wind resistance or the water current.

A rescue party, with knowledge of the direction and speed of ocean currents, can spot the probable location of the distressed vessel many hours after the vessel has reported its location, because this sea anchor will keep the vessel within the bounds of the current and prevent it from drifting across the current in a light wind. When the action of cross winds on the distressed vessel is greater than the force of the current, the drift of the vessel can also be calculated and its new position determined.

In carrying out the invention foldable parachutes with lines attached thereto are provided which can be placed in containers and when needed can be quickly attached to the distressed vessel. These parachutes are removed from their containers and thrown overboard. One end of the line is attached to a life boat or raft and as the wind tends to drive the boat the parachute, which is in the form of a hemispherical pouch that is weighted with lead at its center, opens and serves as a sea anchor, thus greatly decreasing

the distance that the boat would have been driven by the wind and greatly increasing the likelihood of the same being found.

The invention may be understood from the description in connection with the accompanying drawing in which:

Fig. 1 is a side view showing a boat with the sea anchor soon after it has been thrown overboard;

Fig. 2 is a similar view after the boat has drifted to some extent;

Fig. 3 is a side view showing a portion of a shroud line and attached painter;

Fig. 4 is a side view of a portion of the painter line on a larger scale partly in section;

Fig. 5 is a sectional view of a portion of the foldable parachute; and

Fig. 6 is a perspective view of a container for the device.

In the drawing, character 1 indicates a hemispherical pouch of flexible material such as fabric or pliable plastic material. This pouch may be made in sections with the edges of the sections sewed together. A plurality of strands 2 forming a bridle have one end thereof attached to the edge or equator of the pouch 1 at equally spaced intervals. These strands may be made of nylon and they extend through a circumferential row of holes near the edge of a disc 3 of light-weight material such as laminated cork between wood or metal which prevents the strands or bridle lines 2 from becoming wound together if the canopy 4 should be rotated. This disc 3 also gives buoyancy to the apex end of the bridle 2 which supports the canopy 4. A metal weight 4 is secured to the canopy 1 at its center by means of a strip or covering 5 (Fig. 5).

A stranded painter line 6, which may be made of a large number of strands of nylon or other material woven to provide an open core is connected to the strands 2 by loops L provided at the ends of the lines 2 and line 6. One or more buoyant floats 7 are secured within the line 6 at predetermined positions in the outer portion thereof by weaving the strands of line 6 around them. The buoyancy thus provided for the sea anchor unit 1, 2 and 4 is such as to permit it to sink to a predetermined depth. For instance, it can be caused to sink about ten feet below the surface so that it will be in the prevailing current of water. Thus it is below the directional influence of the movement of waves that may be present having a distance of as much as about ten feet or more between the crests and troughs thereof. By placing these floats 7 in the painter 6 or bridle lines 2 near disc 3 that is attached to

the weighted canopy 1, entanglement of the lines 2 that are attached to the canopy 1 is obviated and this canopy is permitted to descend in the water and assume the position to provide instant drag. A hand loop 8 is provided at the other end of line 6 for convenience in attaching to a load or drifting vessel.

A rectangularly-shaped container 9 is provided so that this sea anchor can be folded up and placed therein until needed. The sections 1 may be folded in two groups as indicated in Fig. 6 so as to lie flat with the line 6 also folded and lying between sections, and having the loop 8 hanging out to be readily available through an open edge of the container. After the device has been used it can be refolded and placed in the container 9.

This sea anchor operates as follows under varying wind and current conditions:

(a) In heavy wind pressure that causes rapid drift the vessel will head up into the wind with its drift retarded;

(b) With no wind and deep surface currents, it operates as a drag, pulling the vessel and maintaining its direction with that of the current;

(c) With cross current wind the vessel is caused to head up into the wind and drift with the current. This is the most hazardous circumstance to which occupants of a life raft may be subjected and under which the sea anchor is most beneficial because the sea under these conditions is choppy and most likely to swamp the raft;

(d) A lifeboat with sails may run before a high wind with its jib reefed. This weather condition generally produces a heavy following sea which blankets the sail and may cause the boat to broach-to in a heavy sea and be swamped. This sea anchor thrown off the stern of the boat prevents this danger. In this case the boat is towing the anchor as a drag to hold the stern up into the wind.

What is claimed is:

1. A sea anchor comprising an imperforate, hemispherically-shaped pouch having an imperforate crown portion and a fixed weight of greater specific gravity than water attached to the center of the crown, said entire pouch consisting essentially of flexible sheet-like material and being wholly collapsible, but being adapted to exert retarding force when in expanded condition under water, said weight being arranged so that the interior of the crown is free of substantial projection therein, at least several cords connected to the edge of the pouch at spaced intervals and constituting the sole connection to the pouch, said cords converging substantially equidistantly to an apex region remote from the pouch, and line means connected to said cords at said region, for connecting the sea anchor to a vessel, said cords and line means in series constituting a connecting system providing the sole transmission of retarding force from the pouch to the vessel, said connecting system carrying float means immediately adjacent therewith, including buoyant structure which is remotely spaced from both the edge of the pouch and the end of the line means at the vessel, and said weight at the pouch crown and said float means being cooperatively adapted to hold the pouch

completely below the surface of the water while preventing the connecting system from being drawn entirely vertically below the vessel.

2. A sea anchor comprising an imperforate hemispherically-shaped pouch entirely flexible throughout and wholly collapsible, said pouch being adapted to exert retarding force when in inflated condition under water, connecting line means for connecting the pouch to a vessel, said means consisting of a multiplicity of cords connected to the edge of the pouch at spaced intervals and converging to an apex region remote from the pouch and painter line means connected to the cords at said region and adapted to extend to the vessel, said connecting line means providing the sole transmission of retarding force from the pouch to the vessel, and means for controlling the depth to which said pouch will sink when said pouch and connecting line means are extended in the water, said controlling means comprising float means attached to said connecting line means wholly in close abutment therewith intermediate the ends thereof, and a fixed weight of greater specific gravity than water attached to the center of the crown of the pouch, said weight lying wholly close to the surface of the crown and said pouch being entirely free of lines and connections except at its edge, and the interior of the pouch, upon inflation in the water, thereby constituting a hemispherical cavity of flexible material free of substantial projection therein, and said weight and float means, as constituted in said depth-controlling means, being cooperatively adapted to hold the pouch completely below the surface of the water while preventing the connecting line system from being drawn entirely vertically below the vessel.

3. A sea anchor as described in claim 2, in which the float means includes spacing means for the cords associated with the latter at a locality near said apex region, said spacing means being of less specific gravity than water and thereby having buoyancy for contributing to the depth-controlling action of the pouch depth-controlling means.

4. A sea anchor as described in claim 2, in which the float means comprises a plurality of floats carried by and lying wholly in close abutment with the painter line means at localities spaced along the latter between said apex region and the end of said painter line means remote from said region.
